UNITED STATES PATENT OFFICE.

KARL M. HAMILTON, OF CHICAGO, ILLINOIS, ASSIGNOR, BY MESNE ASSIGNMENTS, TO CHICAGO-CLEVELAND CAR ROOFING COMPANY, OF CHICAGO, ILLINOIS, A CORPORATION OF DELAWARE.

CAR-ROOF CONSTRUCTION.

Application filed June 1, 1920. Serial No. 385,471.

This invention relates to car roofs, and particularly to car roofs of the steel self-sustaining type, formed of roof sheets which extend from eaves to eaves and are lapped and connected together at their side marginal portions.

The objects of the invention are to construct the lapped marginal portions of contiguous roof sheets, so as to impart great strength to the roof as a whole, to prevent leakage between the contiguous roof sheets, and to provide an additional rigidifying means interposed between the lapped marginal portions of the roof sheets.

In addition to the general objects recited above, the invention includes among its objects such other improvements and advantages in construction and operation as are found to contain in the structures or devices hereinafter described or claimed.

In the accompanying drawings forming a part of this specification, and showing, for purposes of exemplification, a preferred form and manner in which the invention may be embodied and practiced, but without limiting the claimed invention specifically to such illustrative instance or instances:

Figure 1 is a plan view of a car roof constructed in accordance with the present improvements;

Figure 2 is an end elevation of the same;

Figure 3 is a detailed vertical section on the line 3—3 of Figure 1;

Figure 4 is a sectional view of the transverse marginal portions of contiguous roof sheets, on the line 4—4 of Figure 1;

Figure 5 is a transverse vertical section on the line 5—5 of Figure 1;

Figure 6 is a detailed vertical section on the line 6—6 of Figure 1;

Figure 7 is a detailed plan view showing the mode of attachment of a running board saddle to the roof.

Figure 8 is a detailed transverse section on the line 8—8 of Figure 1; and

Figure 9 is a fragmentary perspective view of a roof sheet.

The same characters of reference indicate the same parts throughout the several views.

Referring to the drawings, the roof frame

comprises side plates 11 and end plates 12 which are respectively supported in any preferred manner by the sides and ends of a railway car.

In accordance with the present invention, the car roof is constructed of roof sheets 13, of arched form from eaves to eaves of the roof. These roof sheets are preferably constructed of sheet metal and are formed at their eaves ends with laterally-extended flanges 14 merging at their outer edges into depending flanges 15. When assembled on the roof, the laterally-extended flanges 14 overlie the top faces of the side plates and the depending flanges 15 engage the outer side faces of the side plates 11 and function as eaves flashing strips. The transverse marginal portions of contiguous roof sheets are lapped from eaves to eaves of the roof, and said transverse marginal portions are respectively formed with transverse corrugations 16 and 17, extended between the lateral flanges 14 at the eaves ends of the roof sheets and both upstanding from their respective roof sheets. As shown more particularly in Figures 3 and 4 the lapped marginal portions of a pair of contiguous roof sheets 13 are extended transversely of their corrugations 16 and 17 beyond said corrugations, as shown at 18—18, thereby providing a joint, which effectively prevents water from getting in between the lapped corrugations.

The overlapping corrugation 16 of the overlapping marginal portion is formed with an upstanding rib 19 projecting from the apex of said corrugation 16 and extending from eaves to eaves end of its roof sheet and merging into the eaves flange 14 at the opposite eaves ends of the roof sheets, as shown more particularly in Figure 9. On the other hand the underlapping corrugation 17 of the underlapping portion of the other roof sheet is formed with a depending rib 20, projected downwardly from the apex of said corrugation 17 and extended transversely from eaves to eaves end of the roof sheet, but terminating at the inner edges of the flanges 14 at the eaves ends of the roof sheet. These reversely-extended companion transverse ribs 19 and 20 serve to greatly

strengthen the lapped transverse marginal portions of contiguous roof sheets, and the parts are further strengthened by the interposition of a flat filler strip 21 the upper and 5 lower portions of which respectively enter the ribs 19 and 20 and are secured to the side webs of said ribs 19 and 20 by rivets 22 or other suitable securing means. The filler strip 21 is preferably constructed of 10 metal and forms with the companion ribs 19 and 20 and the companion corrugations 16 and 17 of a pair of contiguous roof sheets, a substantially solid carline of great 15 strength. As shown in Figure 5, the filler strip 21 terminates within the eaves ends of the roof. A roof formed in the manner above described is substantially water tight throughout and although of very simple construction, since it may be formed entirely 20 of sheet metal roof sheets shaped by dies, is nevertheless of great strength and possesses a high degree of rigidity for resisting stresses, inasmuch as it embodies in its construction practically solid carlines disposed at frequent intervals along the roof. 25

The roof may be constructed of a plurality of roof sheets of like formation, of the type shown in Figure 9. Each roof sheet is formed at its eaves ends with the trans- 30 versely-extended flanges 14 merging at their outer edges into the depending flanges 15. One transverse marginal portion of a roof sheet is provided with the corrugation 16 having the upstanding rib 19 adapted to overlap 35 the transverse marginal portion of a contiguous roof sheet, whereas, the other transverse marginal portion of the roof sheet is formed with the corrugation 17 having the depending rib 20 adapted to underlap 40 the transverse marginal portion of an opposite contiguous roof sheet.

The end roof sheets are respectively provided with depending transverse flanges 23 which engage the outer faces of and are secured to the end plates 12 by means of 45 bolts 24. The roof sheets are secured at their eaves ends to the side plates 11 by means of bolts 25 passed through the lapped side depending flanges of contiguous roof 50 sheets and through the side plates 11.

For supporting the running board saddles 26 on the roof there is provided, for each running board saddle a pair of clips 27, in the form of Z plates having their portions 55 28 riveted to a side web of the upstanding ribs 19 of the roof sheets. The offset portions 29 of the clips 27 project oppositely from the longitudinal center line of the roof, as shown in Figure 1 and the running board 60 saddle is secured to the oppositely-projecting offset portions 29 of a pair of such clips 27 by means of horizontal bolts 30. The running board 31 is supported in the usual manner on the several running board saddles 26.

65 The invention as hereinabove set forth is

embodied in a particular form of construction, but may be variously embodied within the scope of the claims hereinafter made.

What is claimed is:

1. In a metal car roof, in combination: 70 contiguous roof sheets lapped at their transverse marginal portions and provided with reversely-extended companion ribs respectively formed in said lapped marginal portions, and a filler interposed between the 75 companion ribs of the contiguous roof sheets, substantially as specified.

2. In a metal car roof, in combination: 80 contiguous roof sheets lapped at their transverse marginal portions and provided with reversely-extended companion ribs respectively formed in said lapped marginal portions, and a filler interposed between and 85 secured to the side webs of the companion ribs of the contiguous roof sheets, substantially as specified.

3. In a metal car roof, in combination: 90 contiguous arched roof sheets extending from eaves to eaves of the roof, said roof sheets being lapped at their transverse marginal portions and provided with reversely-extended companion ribs respectively formed in said lapped marginal portions, and a 95 filler interposed between the companion ribs of the contiguous roof sheets, substantially as specified.

4. In a metal car roof, in combination: 100 contiguous roof sheets lapped at their transverse marginal portions and provided with reversely-extending companion ribs respectively formed in said lapped marginal portions, and a filler interposed between the 105 companion ribs of the contiguous roof sheets, the filler terminating within the eaves ends of the roof, substantially as specified.

5. In a metal car roof, in combination: 110 contiguous roof sheets having companion lapped transverse marginal corrugated portions formed with transverse ribs respectively extending reversely to each other, and a filler interposed between the companion corrugated portions of the contiguous roof sheets and entering the reversely-extended ribs formed in said corrugated portions, substantially as specified.

6. In a metal car roof, in combination: 115 contiguous roof sheets lapped at their transverse marginal portions and provided with companion ribs respectively formed in said lapped marginal portions, and a filler interposed between the companion ribs of the contiguous roof sheets, substantially as specified.

7. In a metal car roof, in combination: 120 contiguous roof sheets having companion lapped transverse marginal corrugated portions extended in the same direction from the contiguous roof sheets and formed with transverse ribs respectively extended in reverse direction from the contiguous roof 125 130

sheets, and a filler interposed between the companion corrugated portions of said contiguous roof sheets and entering the reverse-ly-extended ribs formed in said corrugated 5 portions, substantially as specified.

8. In a car roof construction, the combination with the side plates of the roof frame; of contiguous roof sheets formed at their eaves ends with laterally-extended flanges merging at their outer edges into depending flanges, the laterally-extended flanges and the depending flanges respectively adapted to overlie and to engage the top and outer side faces of the side plates; the 10 contiguous roof sheets being lapped at their transverse marginal portions, and provided with an upstanding rib and a companion depending rib, said ribs being respectively formed in said lapped marginal portions, 15 the depending rib terminating at the laterally-extended flanges and the upstanding rib extended over and merging into the laterally-extended flanges; and a filler interposed between the companion ribs of the contiguous 20 roof sheets; substantially as specified.

9. In a metal car roof, in combination: contiguous roof sheets having upstanding companion lapped transverse marginal corrugated portions formed with transverse 30 ribs and projecting beyond the planes thereof, the rib of one roof sheet being extended reversely from the companion rib of the other lapped roof sheet, substantially as specified.

35 10. In a metal car roof, in combination:

contiguous roof sheets having companion lapped transverse marginal corrugated portions, the corrugated portions of each of said sheets being formed with transverse ribs respectively extended in reverse direction from 40 the plane of the sheet from which they are formed, substantially as specified.

11. An arched roof sheet formed at its eaves end with a laterally-extended flange merging into a depending flange, and having its transverse marginal portion formed with a corrugation having a rigidifying rib 45 extending transversely of the roof sheet and beyond the apex of said corrugation, substantially as specified. 50

12. A roof sheet having a transverse marginal corrugated portion at one end formed with a transversely-extended rib projected from said corrugated portion, and having a transverse marginal corrugated portion at 55 the other end formed with a transverse rib projected in the opposite direction from said corrugated portion, substantially as specified.

13. In a metal car roof, in combination: 60 contiguous roof sheets having lapped marginal portions formed with upstanding corrugations, the latter having transverse ribs respectively extending reversely to each other, and the lapped marginal portions of 65 the contiguous roof sheets being extended transversely of and beyond said corrugations, substantially as specified.

KARL M. HAMILTON.
